(57) **CLAIM**

The ornamental design for an automobile wheel, as shown and described.

DESCRIPTION

FIG. 1 is a perspective view of a front, top, and right side of an automobile wheel in accordance with an embodiment of my new design;

FIG. 2 is a perspective view of a front, top, and left side thereof;

FIG. 3 is an enlarged view of a 3-3 portion shown in FIG. 2 thereof;

FIG. 4 is a perspective view of a front and bottom thereof; FIG. 5 is a front view thereof;

FIG. 6 is a rear view thereof;

FIG. 7 is a bottom view thereof; and,

FIG. 8 is a left side view thereof.

The shading in the figures represented on an entire surface portion in each figure is for specifying a three-dimensional shape of the automobile wheel.

A top view of the automobile wheel is a mirror image of the bottom view thereof, and a right side view of the automobile wheel is a mirror image of the left side view thereof.

The broken lines shown in the figures depict portions of the automobile wheel that form no part of the claimed design.
